UNITED STATES PATENT OFFICE.

WALTER H. SCOTT, OF DAYTON, OHIO, ASSIGNOR TO THE DURIRON COMPANY, INC.,
A CORPORATION OF NEW YORK.

DIGESTION APPARATUS.

Application filed September 2, 1924. Serial No. 735,372.

To all whom it may concern:

Be it known that I, WALTER H. SCOTT, a citizen of the United States, and a resident of Dayton, in the county of Montgomery and State of Ohio, have made a new and useful invention in Improvements in a Digestion Apparatus, of which the following is a specification.

The invention relates to digestion apparatus, and particularly to apparatus for carrying away the fumes from the flasks employed in the well known Kjeldahl process. It has for its principal objects the provision of an improved apparatus, (1) in which the flasks may be more easily and conveniently positioned with respect to the fume tube employed and removed from position, (2) in which a better fit is secured between the fume tube and the flasks, so that a smaller fan for carrying away the fumes than that ordinarily required, may be used; and (3) in which the flasks are less subject to breakage during the positioning of such flasks and their removal from operative relation with respect to the fume tube. One embodiment of the invention is shown in the accompanying drawings, wherein:

Figure 1 is a perspective view of the assembled apparatus. Fig. 2 is a partial side elevation and partial longitudinal section through the novel form of fume tube which is employed. Fig. 3 is a section on the line III—III of Fig. 2, with the flask support and one of the flasks shown in dotted lines. And Fig. 4 is a transverse section through a modified form of fume tube having a set of nipples on each side.

Referring to the drawings, 1 is the fume tube and 2 is the flask support, which members are supported from beneath by the two sets of standards 3, 3, 3 and 4, 4, 4. At the upper ends of the standards 3, 3, 3 are suitable T-shaped brackets 5, 5, 5 forked at their upper ends so as to fit around the fume tube. At the left hand end of the fume tube is a suction fan 6 having its inlet coupled to the end of the fume tube. The fan is driven from an electric motor 7, carried by the base 8, and the base is supported upon a pair of pipes 9, 9 having their upper horizontal ends secured in the casting 5. The fumes drawn through the fan are directed through a suitable outlet pipe 10 leading to a vent or chimney or to the outer air.

The flask support 2 is carried by the three

brackets 11, 11, 11, having collars 12 through which the pipe standards 4, 4, 4 extend, the brackets and the support 2 being held at any desired point of vertical adjustment by means of set screws 13 extending through the collars. The brackets 11 are also provided with laterally extending pipe sections 14, which are engaged at their outer ends by brackets having collars 15, through which the standards 3 extend, the collars being provided with set screws 16 for holding the brackets in any desired position of vertical adjustment. The ends of the pipe sections are secured in the brackets by means of the set screws 17, the two sets of standards 3, 3, 3 and 4, 4, 4, being in this manner tied together and mutually braced to give a firm support to the fume tube and the member 2.

Heat is preferably supplied by means of the gas pipe 18 provided with the burners 19, the pipe 18 being supported for vertical adjustment by means of the upright sections 20 extending through collars 21 in the brackets 11, and clamped in position by the set screws 22. The flask support may be adjusted vertically to bring the flasks 28 to proper position with respect to the fume tube, depending on the particular size of flask employed, and the gas burners may be adjusted vertically to give a maximum efficiency in heating effect upon the support and the flasks carried thereby.

The fume tube 1 is of novel construction, in that it is provided with laterally extending inclined nipples 23, integral with the tube section, each section being a unit cast from a corrosion resisting composition, such as high silicon iron, known commercially as "duriron". As illustrated, the tube 1 is made in two sections A and B clamped together by means of a pair of flanges, such as the one marked 24 in Fig. 2. At the outer end of the section B is a header 25, also preferably of corrosion resisting composition, held in place by the clamp 26, having a bolt 27 engaging the header at its center. Any number of tube sections may be employed depending on requirements.

In operation, the flasks 28 are seated upon the support 2 with their laterally opening ends or necks fitting over the nipples 23. The nipples are slightly tapering, so that the flask ends can be moved over them until a relatively close fit is secured. This ar-

arrangement, with the nipples fitting into the flask ends, provides a substantial improvement over the ordinary arrangement, in which the flasks are supported directly beneath the fume tube, with their ends projecting through openings in the lower wall of the tube. With such an arrangement, the fit between the necks of the flasks and the walls of the openings was not close, and considerable breakage was liable to occur in positioning and removing the flasks. With the present arrangement, the fit between the necks of the flask and the tube is improved, so that a smaller fan may be employed to give the required suction, and the convenience, incident to positioning and removing the flasks by merely moving them laterally, is so increased that the breakage incident to these steps is reduced to a minimum. The adjustments of the flask support and burners, heretofore referred to, permits the use of the apparatus with flasks of varying heights, and the fume tube by reason of its construction is practically indestructible.

If desired, the capacity of the apparatus

may be increased, by providing nipples 29 on both sides of the fume tube, as indicated in Fig. 4, in which case, a flask support corresponding to the support 2 is applied along each side of the tube, suitable heating means being also applied.

What I claim is:

1. In combination in apparatus of the class described, a fume tube having laterally and downwardly projecting integral inlet nipples, suction means for the tube, an adjustable flask supporting member paralleling the tube and located below and to one side thereof and adapted to carry a series of flasks having laterally opening necks adapted to fit over the nipples, and heating means beneath the support.

2. In combination a fume tube having fixed thereon a series of tapering nipples extending laterally from the side thereof and inclined downwardly.

In testimony whereof, I have hereunto subscribed my name this 19th day of August, 1924.

WALTER H. SCOTT.
